UNITED STATES PATENT OFFICE.

WILLARD WADSWORTH, OF PLAINFIELD, NEW JERSEY, ASSIGNOR TO
WILLIAM B. WADSWORTH, OF PLAINFIELD, NEW JERSEY.

MEANS FOR CONTROLLING THE LEVEL OF LIQUIDS.

No. 810,237.

Specification of Letters Patent.

Patented Jan. 16, 1906.

Application filed May 6, 1905. Serial No. 259,126.

To all whom it may concern:

Be it known that I, WILLARD WADSWORTH, a citizen of the United States of America, and a resident of Plainfield, county of Union, 5 State of New Jersey, have invented certain new and useful Improvements in Means for Controlling the Level of Liquids, of which the following is a specification, reference being had to the accompanying drawing, forming a part thereof.

My invention relates to means for controlling the level of liquids, and particularly to float-controlled means for this purpose.

The usual method of controlling the level of liquid in tanks is to provide a float-controlled valve for the inlet, the supply therefor being under constant pressure. It is found in practice that it is exceedingly difficult with such an apparatus to hold the liquid in the tank at anything like an even level for many reasons. One reason is that while the pressure of the supply is theoretically constant practically it varies within wide limits, and in so varying the resistance to the buoyancy of the float varies. In an attempt to overcome the practical difficulties in the way of maintaining a uniform level of the liquid intermediate mechanism has been employed which by reason of its great delicacy is itself subject to wide variations or by reason of its complication is impracticable for ordinary purposes.

In my present invention I provide a float which directly controls inlet and exhaust valves for motive fluid, such as compressed air. These inlet and exhaust valves have a vary small movement indeed, infinitely smaller than the necessary movement of an inlet-valve for the liquid. The capacity of these valves is indeed so small that even were the pressure against the inlet-valve varied within far wider limits than is possible the effect on the buoyancy of the float would be practically negligible, and the entire movement of the float of about one-eighth of an inch is all that is necessary for the complete opening and closing of the opposite valves. The inlet and exhaust valves thus controlled are arranged to control admission and exhaust of fluid under pressure to and from a controlling-valve for the pump which is provided for elevating liquid to the tank. By this means I am enabled to absolutely

control the level of the liquid within less than an eighth of an inch, and that in an economical manner with the expenditure of but little power and at small cost.

In order that my invention may be fully understood, I will now describe an apparatus embodying my invention and will then point out the novel features in claims.

The drawing herewith illustrates an apparatus embodying my invention, showing the tank and valve mechanism directly controlled by the float in central vertical section and the other parts in side elevation.

The tank, which may be of any size and shape, is shown conventionally, being designated by the reference character 1, the line 2 designating the level of the liquid therein. A valve-casing 3 is secured to the side of the tank and is provided with inlet and exhaust valves 4 and 5. A pipe 6 supplies fluid under pressure, such as compressed air, constantly from a source of supply, (not shown,) and a pipe 7 acts as a distributing-pipe to convey such motive fluid as is permitted to pass the inlet-valve 4 when such valve is open and the exhaust-valve 5 is closed to a suitable motor or to return such motive fluid from the motor after the inlet-valve 4 is closed and the discharge-valve 5 is open past the discharge-valve 5 to exhaust. The valve 5 is provided with a stem which engages the float-lever 8, pivoted at 9 and provided at its free end with a float 10. Upward movement of the valves 4 and 5 is opposed by a spring 11.

A pump for supplying the tank is shown at 12, a controlling-valve 13 being provided for controlling the supply of fluid-pressure thereto, such as steam. The valve 13 is operated by a fluid-pressure motor 14, fluid-pressure for which is supplied by the aforesaid pipe 7.

In operation the lowering of the level 2 of the liquid in the tank will cause the float 10 to fall, which will effect the closing of the inlet-valve 4 and the opening of the discharge-valve 5, so that fluid under pressure from the motor 14 will be discharged. This will open the valve 13, which will admit steam to the power-pump 12, causing same to elevate water to the tank until finally the level of the tank is restored, when the exhaust-valve 5 will be closed and the inlet-valve 4 opened to

admit motive fluid from the pipe 6 through the pipe 7 to the fluid-pressure motor 14, closing the valve 13 and stopping the pump.

The apparatus while sensitive to very slight variations of the level of the tank is exceedingly positive in its action, but is not at all sensitive to any other variations and conditions. The entire necessary movement of the valves 4 and 5, which are directly engaged by the float, is so small as to stop or start the pump under very small variations in the level of the liquid, while extreme variations in the supply of motive fluid to the pipe 6 or to the pump through the valve 13 will have no effect in varying the conditions under which the parts will operate.

What I claim is—

1. In apparatus of the class described, the combination with a float, and oppositely-disposed inlet and exhaust valves directly engaged thereby, of a pump, a valve controlling motive fluid therefor, a fluid-pressure motor for said controlling-valve, and ducts controlled by said inlet and exhaust valves for admitting fluid under pressure to said motor, and exhausting same therefrom.

2. In apparatus of the class described, the combination with a pump, a valve for controlling motive fluid therefor, and a fluid-pressure motor for said valve, of a float, including a pivoted lever, and inlet and exhaust valves directly engaged by said float-lever, said inlet and exhaust valves arranged for admitting and exhausting fluid under pressure to and from said fluid-pressure motor.

3. In apparatus of the class described, the combination with a pump, a controlling-valve therefor, and a fluid-pressure motor 14 for said valve, of a float 10, a float-lever 8 pivoted at 9 to a valve-casing 3, inlet and exhaust valves 4 and 5, in said casing, and having a stem extending therethrough and engaging the float-lever 8, a spring 11, opposite movements of the valves 4 and 5, and an inlet and distributing pipe 6 and 7 for controlling passage of motive fluid to and from the fluid-pressure motor 14, substantially as set forth.

WILLARD WADSWORTH.
